UNITED STATES PATENT OFFICE.

CHARLES B. ULRICH, OF JAMESTOWN, NEW YORK.

FILING DEVICE.

1,333,231.

Specification of Letters Patent.

Patented Mar. 9, 1920.

Application filed December 16, 1918. Serial No. 266,874.

To all whom it may concern:

Be it known that I, CHARLES B. ULRICH, a citizen of the United States, residing at Jamestown, in the county of Chautauqua 5 and State of New York, have invented a certain new and useful Improvement in Filing Devices, of which the following is a specification.

My invention relates to an improved 10 means for filing data sheets where it is desired to keep different sets of said sheets by themselves although all of the sheets are in the same file and secured therein in such a manner that any sheet of any set is readily 15 available for inspection and that the sheets of any set may be opened from one another in flat relation without disturbing the sheets of the other sets in their relation to each other. My invention is particularly 20 applicable for cases where it is desired to make a permanent file of data sheets belonging to a certain class of subject matter in a single file and at the same time it is desirable to maintain subdivisions or sub- 25 classes in said file so that reference may be made readily to any desired subclass without confusion resulting from the presence of the sheets of the other subclasses in the same file.

My invention consists essentially in providing a flexible filing device in the form of a strip of flexible material of a width slightly greater than the widest or longest sheet to be filed, depending on the manner 30 of placing the sheets in the file, said strip of material being folded transversely first in one direction and then in the opposite direction at regular intervals along the strip, alternate ones of said folded portions being 35 provided with devices for securing to said alternate portions the sheets to be filed, the sheets of each subclass being secured to the same one of said portions and all of the sheets thus secured to the strip preferably 40 pertaining to the same general class of subject matter. As a result of this construction the sheets of each subclass are held in the file by themselves, all of the sheets of the entire class lie upon one and another 45 when the filing device is closed and the sheets of each subclass are separated by the opening of the filing device from the sheets of the other subclasses when the filing device is its open position. Furthermore, the fastening devices employed are of such a nature 50 as to maintain the sheets of each subclass 55

class in substantially the relation to each other of the leaves of a bound book, the principal difference being that the fastening devices employed are preferably flexible and engage the edges of the sheets so that in examining the sheets of any subclass, the sheets may be opened from each other at any desired point and lie in flat position with no tendency to curve the sheets at their fastened edges or to move the sheets to their closed position.

The filing device may be employed alone or it may be secured to a filing card or folder if preferred to protect the device and its attached data sheets and facilitate storing them in a filing cabinet. The device is particularly adapted for use in vertical filing systems although it may be employed effectively in any filing system where the subject matter filed is classified. The device may also be employed apart from any filing system where it is desired to secure a class of data sheets together in a manner to permit ready reference to any sheet of any subclass represented by the sheets secured to the filing device.

My invention will best be understood by reference to the accompanying drawings showing preferred embodiments thereof in which—

Figure 1 is a plan view of a part of the filing device before attaching any data sheets thereto,

Fig. 2 is an edge view of the device shown in Fig. 1,

Fig. 3 is a perspective view of several sheets of one subclass secured to the filing device and shows the filing device secured to a filing holder,

Fig. 4 is an edge view of the filing device and data sheets secured thereto in closed relation and shows also the filing device secured to a folder to inclose the filed sheets,

Fig. 5 is a plan view on a reduced scale of the filing device having several subclasses of sheets secured thereto, said device being secured to a folder and the sheets of the several subclasses being in the position assumed by them separate from each other for the open position of the filing device.

Fig. 6 is a diagrammatic view of a folder with the filing device differently attached thereto from the manner of attachment indicated in Figs. 3, 4 and 5.

Fig. 7 is a view showing another mode of attachment of the filing device and folder,

Fig. 8 shows in a view similar to Fig. 1 a construction of filing device in which three sets of fastening devices are employed for each subclass instead of two sets as shown 5 in Fig. 1, and

Fig. 9 shows in a view similar to Fig. 1 a modified construction of filing device in which the fastening devices are separated slightly from each other to cause the sheets 10 filed in the device to occupy a minimum space in the direction of the thickness of the sheets or folder when the device is in its closed position.

Similar numerals refer to similar parts 15 throughout the several views.

As shown in Figs. 1 and 2, the filing device consists of a strip of material 10 which may readily be folded at the fold lines 11 and 12 so that the strip may readily be 20 moved to its open or flat position and closed to the position indicated in Fig. 4. I find that cloth answers admirably for this purpose. The right hand portion of the strip 10 shown in Figs. 1 and 2 forms a flap 13 which is preferably coated with glue to 25 facilitate securing the filing device to a filing card or folder although I do not limit myself to this means of securing the parts together. Following the portion 13 along 30 the strip are the successive portions 14 and 15, which may be narrow relatively to their length, the length of these portions being equal to the width of the strip 10. Each of the portions 14 is preferably coated with 35 glue and provided with cuts 16 there-through extending longitudinally of the strip 10 to leave tongues 17 connected to the strip at their right hand ends as shown in Fig. 1 along the fold line 12. At their other 40 ends the tongues 17 are separated from the portion 14 by short diagonal cut 18 nearly but not quite freeing the ends of the tongue from the portion 14 as a result of which the tongues may be lifted as desired 45 by means of a pointed instrument such as the point of a knife blade and their left hand ends readily torn from the portion 12. It is to be noticed that the tongues 17 shown in Fig. 1 are in two groups, one above the 50 middle line of the strip 10 and the other below the middle line and there are as many tongues in each group as the number of data sheets provided for by the filing device in each subclass. Each of the portions 15 is preferably reinforced and stiffened by 55 securing thereto a narrow strip of flat stiff material such as cardboard or fiber 19 which materially assist in causing the filing device to fold properly along the lines 11 and 12 when the device is moved to its closed 60 position.

In securing the data sheets 20 to the filing device as shown in Fig. 3 the first tongue 17 is separated at its left hand end from 65 the portion 14 and fastened to the first

sheet, the second tongue of each group is fastened to the second sheet and so on as a result of which each sheet is secured at two points separated a considerable distance from each other to the filing device by the 70 tongues secured to it which tongues constitute hinges at the edge of the sheet adjacent the fold line 12 and permit the sheets to be readily separated from each other and moved to flat position in which position 75 the sheets readily remain for inspection since there is no tendency on the part of the supporting tongues to move the sheets to their closed position.

As shown in Fig. 3 the flap 13 is secured 80 to the end of a folder 21, of a size slightly larger than the largest sheet to be filed in the filing device as a result of which when the filing device is in its closed position, said device and its attached sheets may be entirely contained within the folder which, for filing purposes may be provided with an indexing tab 22 if desired.

As shown in Fig. 5 when the filing device with several sheets in several subclasses attached thereto is in open position the sheets of the several subclasses 23, 24 and 25 are separated at their right hand ends a distance equal approximately to the distance between adjacent ones of the fold lines 12, thus making the sheets of each subclass readily available for inspection without handling the sheets of the other subclasses in locating the desired subclass. It will at once appear that additional sheets may be 100 attached in any subclass regardless of the number of sheets in the other subclasses, that is to say the fastening devices of each subclass are as readily available at all times for attaching additional sheets in said 105 subclass to the filing device as though no other subclasses of sheets were present.

When the filing device is to be placed in a cabinet or otherwise stored, it is folded along the fold lines referred to as indicated in Fig. 4, thus making a compact arrangement of the sheets protected for filing purposes by the inclosing folder.

As a result of the tongues being displaced from each other in each subclass, it will be 115 observed that the tongues when attached to the corresponding sheets of a subclass do not build up upon each other but that the total thickness on the other hand is little, if any more than the combined thickness 120 of the sheets of the subclass and the single thickness of the tongues. Where the sheets filed are relatively thick, or for any other reason it is desired to insure that the closed file shall have a minimum thickness the 125 modified construction of filing device 10a shown in Fig. 9 may be employed which is the same as the filing device above described with the single exception that the 130 tongues 17a are separated from each other

somewhat, thus affording the filed sheets a better opportunity to bend slightly at the filing edge from one plane to another.

As indicated in Fig. 6 the filing device 5 10 may be secured to the folder 21 at or near the fold line of the folder instead of to one end of the folder as shown in Figs. 3, 4 and 5, and again if preferred the filing device may be secured to one of the 10 side edges of the folder as shown in Fig. 7.

My improved filing device thus lends itself readily to a wide variety of uses and in any event the construction and operation of the filing device is substantially the 15 same. It is to be noted that the end portion 26 of the filing device constitutes a convenient flap by means of which the device may be moved from its closed to its open position.

20 For certain purposes, as for example for filing large sheets, it may be desirable to fasten each sheet to the filing device more securely than above described, and in this case, a modified form of filing device 10^b 25 shown in Fig. 8 may be employed, which is of the same construction and operation as the filing device above described, with the exception that each portion 14^a of the wider strip of the filing device is provided with 30 three groups of tongues 17^b, one tongue of each group to be secured to each sheet filed.

While I have shown the filing strips 10, 10^a and 10^b adapted for folding to reduce the file and its contents to small bulk, it 35 will be understood that the same construction may be employed without folding said strips where it is desirable to do so for special uses.

While I have shown my invention in the 40 particular embodiments above described it is to be understood that I do not limit myself to these exact constructions, as I may employ any equivalents thereof known to the art at the time of the filing of this 45 application without departing from the scope of the appended claims; for example, I find in some cases it is not necessary to employ the reinforcing strips 19 and again the tongues referred to may be entirely 50 severed at one end from the adjacent portion of the filing device. Similarly, any desired means may be employed for securing the filing device to a backing or folder in any manner and relation that will best 55 serve the needs of any particular case.

What I claim is:

1. In a filing device, the combination of 60 a strip of flexible material having fold lines extending transversely across it dividing said strip into a plurality of rectangular portions, alternate ones of said portions being provided with cuts through them extending longitudinally of said strip and forming tongues connected to said strip 65 along alternate ones of said fold lines,

whereby said tongues of each of said alternate portions may be secured to sheets in one subclass of the matter to be filed in said device, and reinforcing strips secured to the intermediate ones of said portions. 70

2. In a filing device, the combination of a strip of flexible material having fold lines extending transversely across it dividing said strip into a plurality of rectangular portions, alternate ones of said portions being provided with cuts through them extending longitudinally of said strip and forming tongues connected to said strip along alternate ones of said fold lines, 75 whereby said tongues of each of said alternate portions may be secured to sheets in one subclass of the matter to be filed in said device, and reinforcing strips secured to the intermediate ones of said portions, 80 said tongues being coated with glue to facilitate securing them to said sheets. 85

3. In a filing device, the combination of a strip of flexible material having fold lines extending transversely across it dividing said strip into a plurality of rectangular portions, alternate ones of said portions being provided with cuts through them extending longitudinally of said strip and forming tongues connected to said strip along alternate ones of said fold lines, 90 whereby said tongues of each of said alternate portions may be secured to sheets in one subclass of the matter to be filed in said device, reinforcing strips secured to the intermediate ones of said portions, and a back- 95 ing member secured to the end of said strip. 100

4. A filing device comprising a strip of flexible material having fold lines extending transversely across it dividing said strip into a plurality of rectangular portions, alternate ones of said portions being provided with cuts through them extending longitudinally of said strip and forming tongues connected to said strip along alternate ones of said fold lines, whereby said 110 tongues of each of said alternate portions may be secured to sheets in one subclass of the matter to be filed in said device. 115

5. A filing device comprising a strip of flexible material having fold lines extending transversely across it dividing said strip into a plurality of rectangular portions, alternate ones of said portions being provided with cuts through them extending longitudinally of said strip and forming tongues 120 connected to said strip along alternate ones of said fold lines, whereby said tongues of each of said alternate portions may be secured to sheets in one subclass of the matter to be filed in said device, said tongues 125 being coated with glue to facilitate securing them to said sheets.

6. In a filing device, the combination of a strip of flexible material having fold lines extending transversely across it dividing 130

4
said strip into a plurality of rectangular portions, alternate ones of said portions being provided with cuts through them extending longitudinally of said strip and 5 forming tongues connected to said strip along alternate ones of said fold lines, whereby said tongues of each of said alternate portions may be secured to sheets in one subclass of the matter to be filed in said 10 device, and a backing member secured to the end of said strip.

7. In a filing device, the combination of a strip of flexible material having fold lines extending transversely across it dividing 15 said strip into a plurality of rectangular portions, alternate ones of said portions being provided with cuts through them extending longitudinally of said strip and forming tongues connected to said strip along alternate ones of said fold lines, whereby said tongues of each of said alternate portions may be secured to sheets in one subclass of the matter to be filed in said 20 device, and a backing member secured to the end of said strip.

25 8. In a filing device, the combination of a strip of flexible material having fold lines extending transversely across it dividing said strip into a plurality of rectangular portions, alternate ones of said portions being provided with cuts through them extending longitudinally of said strip and forming tongues connected to said strip along alternate ones of said fold lines, whereby said tongues of each of said alternate portions may be secured to sheets in one subclass of the matter to be filed in said 30 device, and reinforcing strips secured to the intermediate ones of said portions, said tongues of each alternate portion being arranged in a plurality of groups to facilitate the use of a tongue of each group in securing a paper in the filing device.

35 9. In a filing device, the combination of a strip of flexible material having fold lines extending transversely across it dividing said strip into a plurality of rectangular portions, alternate ones of said portions being provided with cuts through them extending longitudinally of said strip and forming tongues connected to said strip along alternate ones of said fold lines, whereby said tongues of each of said alternate portions may be secured to sheets in one subclass of the matter to be filed in said device, and reinforcing strips secured to the intermediate ones of said portions, said 40 tongues being coated with glue to facilitate securing them to said sheets, said tongues of each alternate portion being arranged in a plurality of groups to facilitate the use of a tongue of each group in securing a paper in the filing device.

45 10. A filing device comprising a strip of flexible material having fold lines extending transversely across it dividing said strip into a plurality of rectangular portions, alternate ones of said portions being provided with 50 cuts through them extending longitudinally of said strip and forming tongues connected to said strip along alternate ones of said fold lines, whereby said tongues of each of said alternate portions may be secured to sheets in one subclass of the matter to be filed in said device, said tongues being coated with glue to facilitate securing them to said sheets, said tongues of each alternate portion being arranged in a plurality of groups to facilitate the use of a tongue of each group in securing a paper in the filing device.

10. A filing device comprising a strip of flexible material having fold lines extending transversely across it dividing said strip into a plurality of rectangular portions, alternate ones of said portions being provided with 70 cuts through them extending longitudinally of said strip and forming tongues connected to said strip along alternate ones of said fold lines, whereby said tongues of each of said alternate portions may be secured to sheets in one subclass of the matter to be filed in said device, said tongues being coated with glue to facilitate securing them to said sheets, said tongues of each alternate portion being arranged in a plurality of groups to 80 facilitate the use of a tongue of each group in securing a paper in the filing device.

11. In a filing device, the combination of a strip of flexible material having fold lines extending transversely across it dividing 85 said strip into a plurality of rectangular portions, alternate ones of said portions being provided with cuts through them extending longitudinally of said strip and forming tongues connected to said strip along alternate ones of said fold lines, whereby said tongues of each of said alternate portions may be secured to sheets in one subclass of the matter to be filed in said device, reinforcing strips secured to the intermediate 90 ones of said portions, and a folder having its edge portion secured to one end of said strip to inclose said strip and the papers secured thereto in closed condition.

12. In a filing device, the combination of 100 a strip of flexible material having fold lines extending transversely across it dividing said strip into a plurality of rectangular portions, alternate ones of said portions being provided with cuts through them extending longitudinally of said strip and forming tongues connected to said strip along alternate ones of said fold lines, whereby said tongues of each of said alternate portions may be secured to sheets in one subclass of the matter to be filed in said device, and a folder having its edge portion secured to one 105 end of said strip to inclose said strip and the papers secured thereto in closed condition.

13. In a filing device, the combination of 110 a strip of flexible material having fold lines extending transversely across it dividing said strip into a plurality of similar portions, alternate ones of said portions being provided with devices for separately securing sheets to said device, and reinforcing strips secured to the intermediate ones of 115 said portions.

14. In a filing device, the combination of a strip of flexible material having fold lines 125 extending transversely across it dividing said strip into a plurality of similar portions, alternate ones of said portions being provided with devices for separately securing sheets to said device, reinforcing strips 130

secured to the intermediate ones of said portions, and a folder having its edge portions secured to one end of said strip to inclose said strip and the papers secured thereto in closed condition.

15. In a filing device, the combination of a strip of flexible material having fold lines extending transversely across it dividing said strip into a plurality of similar portions, alternate ones of said portions being provided with devices for separately securing sheets to said device, reinforcing strips secured to the intermediate ones of said portions, and a backing member secured to said

15 strip of flexible material.

16. A filing device comprising a strip of flexible material having a plurality of rectangular portions, alternate ones of said portions having cuts through them extending 20 longitudinally of said strip to form tongues in each said alternate portion for securing sheets thereto in one subclass of the matter to be filed in said device.

17. A filing device comprising a strip of 25 flexible material having a plurality of rectangular portions, alternate ones of said portions having cuts through them extending longitudinally of said strip to form tongues

in each said alternate portion for securing sheets thereto in one subclass of the matter 30 to be filed in said device, and reinforcing means secured to the intermediate portions of said strip.

18. A filing device comprising a strip of flexible material having a plurality of rectangular portions, alternate ones of said portions being provided with devices for separately securing sheets to be filed in separate groups, and reinforcing means secured to the intermediate portions of said strips. 35

19. A filing device comprising a strip of flexible material having a plurality of rectangular portions, alternate ones of said portions having cuts through them extending longitudinally of said strip to form tongues 45 in each said alternate portion for securing sheets thereto in one subclass of the matter to be filed in said device, said tongues of each alternate portion being arranged in a plurality of groups to facilitate the use of a 50 tongue of each group in securing a paper in the filing device.

In witness whereof, I hereunto subscribe my name this 26th day of November, A. D. 1918.

CHARLES B. ULRICH.
